WRAPPING AND BANDING MACHINE

Francis X. Malocsay, Upper Saddle River, N. J., assignor, by mesne assignments, to Consolidated International Corporation, a corporation of New York

Application February 3, 1932, Serial No. 590,571

9 Claims. (Cl. 93—2)

This invention relates generally to article wrapping and banding machines, and while broadly applicable, is particularly concerned with the wrapping of cigars in cellophane paper and the 5 banding of said cigars.

It is among the objects of this invention to provide a wrapping and banding machine which will entirely wrap an article and secure a band around the wrapper, said wrapper being held 10 about the article by means of an interlocked seam, thereby entirely eliminating the use of heat or an adhesive.

Another object of the invention is to provide a mechanism which will automatically deliver said 15 article to the wrapping and banding position, and which will automatically discharge said article after it has been wrapped and banded.

Another object of the invention is to produce a mechanism which wraps or envelops cellophane 20 or other enveloping material around a cigar and which neatly interlocks the seam edges of the wrapper and folds the ends of such wrapper automatically at high speed.

Another object of the invention is the provision 25 of means for applying a wrapper around a cigar, said wrapper being held in position about the cigar solely by means of an interlocking seam formed by the edges of said wrapper.

Another object of the invention is the provision 30 of means for applying a wrapper around a cigar, said wrapper being held in position about the cigar solely by means of an interlocking seam formed by the edges of said wrapper, said interlocking seam formed parallel to the axis of the cigar, said 35 folded wrapper having its ends extending beyond the extremity of the cigar creased and folded to maintain the wrapper in position about the cigar and to complete the wrapping or sealing thereof.

Another object of the invention is to provide a combination wrapping and banding machine which can be easily and quickly adjusted to entirely wrap an article and discharge it without securing a band around said article and wrapper, or, 45 be so adjusted to discharge a banded but unwrapped article.

Another object of the invention is to provide a cigar handling mechanism which will place a 50 wrapper and a band around a cigar in synchronous operation with a wrapper and band feed mechanisms.

A further object of this invention is to provide a combination cigar wrapping and banding mechanism which will accommodate cigars of various 55 shapes and sizes and which will be particularly

adapted for synchronous cooperation with any of the conventional cigar feeding devices, commonly known as hoppers.

Another object of this invention is to provide a cigar wrapping and banding mechanism which will receive a wrapper and band placed one upon the other, and which will fold said wrapper around the cigar and fold its edges in an interlocked seam, and then band it without moving said cigar to 5 perform both folding operations.

Another object of the invention is to provide a wholly coordinated and combined assembly by 10 which the foregoing objects are carried out in a novel, simple and improved manner and thereby increase the production and reduce the cost of 15 wrapping and banding cigars.

Another object of the invention is to provide a wrapping and banding machine in which the entire operation is automatic and does not require 20 human handling of the articles and which thus greatly reduces the amount of manual labor or supervision required.

A further object of my invention is to provide and construct in a single unit a combined wrapping and banding mechanism; that is, a machine 25 which will at a certain definite and predetermined position perform the dual function of applying a wrapper and a band around a cigar, said wrapper being sealed by an interlocking fold without the employment of heat or an adhesive. 30 In the present practice two independent mechanisms are utilized; one for the purpose of applying the band, like that illustrated in my Patent No. 1,261,832, dated April 9, 1918, from which the cigars are conveyed to a wrapping mechanism 35 where the wrapper is applied, like that disclosed in my copending application filed November 29, 1930, Serial No. 498,992. A cigar being a very brittle and fragile article, it can be easily crushed and its tobacco wrapper injured and destroyed, 40 and in practice it has been found that where two mechanisms are utilized there is a great breakage of cigars because of the transportation from the banding mechanism to the wrapping mechanism. There is also a great wastage of bands and 45 wrappers. These various objections have been overcome by my combined wrapping and banding mechanism.

Another object, concurrent with the last named, is to provide a mechanism whereby all the 50 different operations required for the wrapping, sealing and banding of the cigar are performed in one spot with the cigar held stationary. This has not only the advantage of sparing the cigar from possible damage by transportation, but with 55

- a recalcitrant and somewhat resilient wrapping material, such as "Cellophane", an interlocking seam can be executed successfully only when the supplementary means of sealing the wrapper, i. e. 5 the twisting and doubling down of the wrapper end extensions, as well as the additional belting by the surrounding band, are applied immediately after forming the doubled seam without further delay by transportation or change of gripping elements, so that the seam cannot unlock again. For this reason the so-called turret machines which wrap cigars or packages progressively in different stations, although they can handle tin foil wrappers or common paper successfully, even with an interlocking joint, would not be satisfactory in the present case. In the present state of the art, where they handle "Cellophane" wrappers, they usually employ simple lap joints or seal the seams by heat or paste. 10 Other more specific objects and advantages of the apparatus will appear as the nature of the improvements are better understood, the invention consisting substantially in the novel arrangement and correlation of instrumentalities herein 15 fully described and illustrated in the accompanying drawings wherein similar reference characters are used to describe corresponding parts throughout the several views and then finally pointed out and specifically defined and indicated 20 in the appended claims.
- The disclosure made the basis of exemplifying the present inventive concept suggests a practical embodiment thereof, but the invention is not to be restricted to the exact details of this disclosure, and the latter, therefore is to be understood from an illustrative, rather than a restrictive standpoint. It will be understood that the various features of the invention may be separately applicable despite their cooperation herein 25 shown.
- In this specification no detailed description of the operation of the wrapper and band feed mechanisms will be made as those mechanisms do not form a specifically claimed part of the 30 present patent application, and no detailed description of the operation of the cigar feed or hopper mechanism will be made, as this type of mechanism is fully described and illustrated in my Patent No. 1,653,641, dated December 27th, 35 1927, and in my applications, Serial Number 492,437, filed October 31, 1930, on Cigar banding machines; Serial Number 519,347, filed March 2, 1931, on Cigar handling machines; and Serial Number 526,788, filed April 1, 1931, on Cigar 40 machines.
- In the embodiment of the invention as herein disclosed there is provided a table, upon the top of which the cigars are fed from a hopper which is not shown in the drawings, but which would be located at the left hand side of Fig. 1 and operated in a synchronous manner with the wrapping, interlocking seam folding and banding operation. The cigars move with an intermittent movement. The rest periods between the forward movements of the cigars being equal to one complete cycle of the wrapping, folding and banding mechanism. The cigars are guided upward between adjustable guides by a plunger. This upward movement causes the wrapper and 50 band to be wrapped around three sides of the cigar with the aid of certain automatically adjusted side plates. The cigar is held in this position while the wrapper and band are folded around the fourth side of the cigar. At the completion of this operation, the ends of the folded

5 wrapper which extend beyond the ends of the cigars are folded together and bent downward which completes the wrapping and banding of the cigar. All of the parts which comprise this wrapping, interlocking fold and banding mechanism are driven directly or indirectly from a common drive mechanism which is not shown in the drawings, as it forms no part of this invention, and this drive mechanism also serves to drive the cigar, wrapper and band feed mechanism with which it will cooperate. 10

The combination wrapping, interlocking fold and banding mechanism illustrated in the accompanying drawings will function in the same manner as described hereinafter whether it is 15 to be utilized purely as a cigar wrapping mechanism or a banding mechanism. The wrapper and band feed mechanisms, although not shown, will be located directly behind the wrapping, interlocking fold and banding mechanism; and in 20 such order that the band will be placed upon the wrapper. These mechanisms, as stated above, are driven from a common source, and it is at this point that a simple and effective clutch or transmission is located to transmit the power 25 to these mechanisms. By manipulation of this clutch or transmission the wrapper feed mechanism can be quickly thrown out of operation and a banded and unwrapped cigar will be ejected, and likewise, by throwing the band feed 30 mechanism out of operation, a wrapped but unbanded cigar will be ejected. With these adjustments in mind, it is readily seen that should it be so desired, cigars could first be banded and then fed through the mechanism a second time 35 to be wrapped. This method of operation places the band directly around the cigar instead of around the wrapper. I also wish to state at this time that this mechanism is also applicable to that type of wrapper for a cigar upon which 40 a facsimile of a band has been printed, said type of wrapper being fully described in my co-pending application filed March 31st, 1931, Serial No. 526,632.

In connection with the features hereinafter 45 specifically pointed out, and in addition to the many unique and improved structural combinations, the invention is also concerned with the specific mechanical means by which the various 50 advantageous functions are achieved; said mechanical means being combined to provide an automatic, simple, inexpensive, rugged and durable apparatus.

The inventive idea involved is capable of receiving a variety of mechanical expressions, one 55 of which for the purpose of illustration is shown in the accompanying drawings, in which—

Fig. 1 is a front elevation, partly broken away, of my improved wrapping and banding mechanism; 60

Fig. 3 is a sectional plan view taken on the line 3—3 of Fig. 2;

Fig. 4 is a detail sectional view taken on the 65 line 4—4 of Fig. 2 illustrating the position of the wrapping, interlocking fold and banding elements at the start of the wrapping and banding operation;

Fig. 5 is a detail sectional view illustrating 70 the position of the wrapping, interlocking fold and banding elements during the first step of the wrapping and banding operation;

Fig. 6 is a similar view illustrating the completion of the first wrapping and banding step. 75

Fig. 7 is a sectional side view taken on the line 7—7 of Fig. 6; which illustrates the position of the end folders with respect to the wrapper when it is in the position shown in Fig. 6;

Fig. 8 is a detail sectional view illustrating the beginning of the second step of the wrapping operation which shows how the sides of the wrapper are folded around the bottom of the cigar by the seam folders and illustrates the first 10 step of the seam interlocking operation;

Fig. 9 is a similar view which illustrates the second step of the seam interlocking operation;

Fig. 10 is a view similar to Fig. 9 illustrating the third step of the seam interlocking operation;

Fig. 11 is an enlarged detail view which illustrates more clearly the relative positions of the seam folders and the sides of the wrapper during the first step of the seam interlocking operation 20 as illustrated in Fig. 8;

Fig. 12 is a similar view illustrating the relative positions of the seam folders and the sides of the wrapper during the second step of the seam interlocking operation as illustrated in

Fig. 9;

Fig. 13 is a view similar to Figs. 11 and 12 which illustrates the third step of the seam interlocking operation as illustrated in Fig. 10;

Fig. 14 is a plan view partly broken away 30 illustrating part of the interlocking seam folders;

Fig. 15 is a sectional side view taken on the line 15—15 of Fig. 10 which illustrates the position of the lower end folders after the wrapper 35 has been folded under the cigar and the seam interlocked as shown in Fig. 10;

Fig. 16 is a detail sectional view illustrating the completed interlocked seam fold and the first 40 part of the step of folding the ends of the band under the cigar;

Fig. 17 is a similar view illustrating the completion of this banding step;

Fig. 18 is a sectional side view taken on the line 18—18 of Fig. 17 illustrating the end folding 45 of the wrapper;

Fig. 19 is a detail sectional view illustrating the position of the parts prior to the ejecting of the wrapped and banded cigar, and a second cigar with its wrapper and band in position;

Fig. 20 is a side view illustrating the completely wrapped and banded cigar; and

Fig. 21 is a bottom view of Fig. 20.

With particular reference to Figs. 1, 2, and 3, numeral 1 represents a table upon which my 55 wrapping, interlocking seam folding and banding mechanism is mounted, and upon which the cigars 2 are moved toward said mechanism from a cooperating hopper not shown, but which is also mounted upon the table. The cigars move 60 forward with an intermittent movement from the hopper upon a conveyor; the surface speed of which is slightly greater than is necessary to feed the cigars up to the wrapping and banding position as shown in Fig. 1, and it is because 65 of this slightly greater surface speed that any space between the individual cigars is gradually eliminated, and the cigars kept in close contact with one another as they approach the wrapping, interlocking seam folding and banding 70 mechanism. A slight slippage between the cigars and the conveyor insures their close contact and prevents jamming. The first cigar is brought into contact with a centering plate 3 which protrudes upward through the table and in the path 75 of the cigars as shown in Fig. 1. This centering

plate 3 is linked to the centering plate 4 at its lower extremities (not shown) in such a manner as to insure equal spread of these plates when the plunger 5 pushes the cigar upward between them as illustrated in Fig. 4. The centering plate 5 10 4 has the downwardly extending legs 6 to which the plate 4 is linked, and which are far enough apart to allow the cigars to pass between them. The outwardly extending flange 7 is integral with the plate 4 and acts as a guide.

Lying across the top edges of the centering plates 3 and 4 is the cigar wrapper 8 and the band 9. The outer ends of the wrapper and band are supported by the supports 10 and 11. Directly above the wrapper and band, and centrally located between the two centering plates is a plunger 12 having the presser feet, 12^a and 12^b extending outward from its center which is cut away to span the rod 13, which is clearly illustrated in Fig. 2 and the end of the ejector finger 20 104 as illustrated in Figs. 1, 3, 17, and 19. The plunger 12 is slidably mounted in a guide comprised of the upwardly extending bracket 14 and the retaining plates 15 which are held in position by the screws 16. Extending outward from sides of the plunger plate 12 and located at its uppermost extremity are the spring supporting pins 17. (See Figs. 1, 2, and 3). Around the ends of these pins and in suitable grooves are hooked the light coil springs 18, the lower ends 30 of which are secured in suitable grooves in the ends of the anchor pins 19 which are carried in the casting 16. The purpose of these springs is to push the plunger downward with just enough 35 force to prevent the wrapper and band from slipping when a cigar is pushed upward into the position as illustrated in Figs. 4, 5, and 6.

Located at the left hand side of the plunger 12 (Fig. 1) is the plate 20 which is mounted upon the rod 21 slidably mounted in the bearings 22 40 and 23 which are a part of the bracket 14, and the top surface of said plate is in sliding contact with the machined bottom surface 24 of the bracket 14 which prevents the plate from turning about the axis of its supporting rod 21. Integral with the rear surface of the plate 20 and located near its ends are the lugs 25 to which are hinged the connecting links 26 by means of the shouldered screws 27 (see Figs. 1 and 3). The opposite ends of these links 26 are hinged to 50 one side of the toggle levers 28 by the shouldered screws 29. The toggle levers are pinned securely upon the shaft 30 mounted in the bearing 31, integral with a portion of the bracket 14. The shaft 30 extends beyond the rear toggle 55 lever as illustrated in Fig. 3, and upon this extension is secured the lever 32. Fastened to the end of this lever is the push rod 33 which is moved up and down by a cam which is part of 60 the band feed mechanism not shown in the drawings. Fastened to the extensions 34 of the toggle levers 28 are the connecting rods 35; the upper ends of which are connected to the lever 36 secured upon the shaft 37. The shaft 37 is carried in the bearing 38 integral with the top of 65 bracket 14 (Fig. 1) and has secured to its outer ends, the arms 39. Hinged to these arms by means of the screws 40 are the connecting arms 41 of the bell crank 42. Integral with the center 70 of the bell crank 42 are the lugs 43, between which is connected the link 44 by means of the pivot screw pin 45. The lower end of link 44 is connected to the lever 46 by the pivot screw 47. The lever 46 is mechanically connected to 75

a cam, not shown, which is part of the main drive mechanism. The bell crank 42 is secured to top of the plate 48 by means of the shaft 49 and the bearing blocks 50. Hinged to the plate 48 are the connecting links 53. These links pass through suitable apertures 55 cut in the plate and are connected to the hinge blocks 51 by the screw pins 52. The other ends of the connecting links 53 are connected to the toggle levers 28 by the screw pins 54. The combination of links 26 and 53, the toggles 28, links 35, arms 36, levers 39 and bell crank 42 impart a parallel movement to the plates 20 and 48 when the push rod 33 is actuated.

15 The rocker arm 56 is supported on the pin 57 mounted in the boss 58 of the bracket 14 (see Fig. 1). Secured upon a rearwardly extending portion of the shaft 57 is the lever 59 to which is connected the push rod 60 which extends 20 downward and is mechanically connected to a cam, not shown, but which is part of the main drive mechanism. The upper end 61 of the rocker arm 56 has secured to it the flat spring 62; the purpose of which is to exert a pressure upon the 25 plunger retaining pin 63, slidably mounted in the boss 64 of bracket 14 when the lower end of said rocker arm is swung in a clockwise direction as illustrated in those steps of the wrapping and banding operation shown in Figs. 6, 8, and 9.

30 This pressure against said pin 63 causes it to bear against the plunger 12 which holds it in position against the pull of the coil springs 18 when the plunger 5 moves downward and away from the bottom of the cigar.

35 Hinged to the lower end of the rocker arm 56, by means of the pin 65 and the lugs 66, is the band folding finger 67. This finger is held in its normal position as shown in the various views by the flat spring 68 pressing against the tongue 69 integral with said finger; said flat spring being secured to the rocker arm 56. Suspended between two projections which form the front end of the finger 67 is the roller 70, and suspended upon the pin 65 and located between the lugs 66 is the 40 roller 71, the purpose of these rollers and the finger being fully described hereinafter.

45 Driven into the upper end 61 of the rocker arm 56 is the anchor pin 72 to which is hooked the light coil spring 73 (see Fig. 1). To the lower 50 end of this coil spring is hooked the fabric tape 74 which passes around the roller 71 and between the side flanges of the finger 67 to the under side of the plunger foot 12 where it is anchored by pushing its rolled and sewed end into the slotted 55 hole 75 for that purpose, which is clearly illustrated in Fig. 4. Also anchored in this same slotted hole 75 is the rolled and sewed end of the fabric tape 74a which passes under the plunger 60 foot and around a roller 76 carried in a cut-out portion in the bottom of the pressure plate 48. The upper end of this tape 74a is hooked to the coil spring 73a which is similar to coil spring 73, the upper end of which is anchored to the hook 77 which is fastened in the bell crank 42.

65 Secured to the plunger plate 12 (see Fig. 1) is the bracket 78 having the pin 79 engaging in the slot 80 of the pusher link 81 which is connected to the lever 82 by means of the pin 83. The lever 82 is pivotally connected to the bracket 84 which is fastened to the extension of bracket 14. Also connected to the lever 82 is the push rod 85 which is mechanically connected to a cam, not shown, which is a part of the main drive mechanism.

70 75 The purpose of this push rod, lever link and

bracket is to move the plunger 12 upward to allow the completely wrapped and banded cigar to be easily removed as illustrated in Fig. 19. The lever 46 with its link 44 are provided to raise the plate 48 for the same purpose, which is also illustrated in Fig. 19.

Slidably mounted in side frames 86 is the seam folder plate 87, which is apertured at 88 (see Figs. 3, 4, and 14) to allow for proper positioning of the finger 67 and to allow for free movement between the rocker arm 56 and said plate when said plate is moved forward as illustrated in Figs. 8 and 9. A further object of said aperture 88 will be more fully described hereinafter. Toward the rear of the seam folder plate 87 and centrally located (see Fig. 3) is secured the gear rack 89 which engages with the gear sector 90 arranged above the rack and pinned upon the shaft 91 mounted in the bearings 92 which are integral with the side frames 86. Upon the rear end of the shaft 91 is secured the arm 93 to which is connected the push rod 94. This rod is mechanically connected to a cam which is not shown, but which is a part of the main drive mechanism of the machine. The collar 95 on shaft 91 prevents the shaft from sliding and thereby preventing the rack and gear sector from disengaging. An up and down movement applied to the push rod 94 by its operating cam (not shown) causes the seam folder plate 87 to move forward and backward in proper synchronization with the rest of the mechanism. The forward or leading edge 87a of the seam folder plate 87 is beveled downward and rounded at the point; the purpose of this beveled edge being more fully described hereinafter. Slidably mounted upon the top surface of the seam folder plate 87 is the preliminary seam folder plate 117, the front edge of which extends beyond the beveled edge 87a of the plate 87. This preliminary seam folder plate 117 is made of thin spring steel and apertured as at 88a to correspond to the aperture 88 of the plate 87 (see Figs. 3, 4, and 14). The plate 117 is retained in proper alignment by the two stop screws 118 and the combination anchor and guide screws 119, the shanks of which pass through the guide slots 120 cut in said plate 117 (see Figs. 3 and 14) and are screwed into the plate 87. The rear ends of the guide slots 120 are held against the stop screws 118 by the coil springs 121 which are hooked at one end in suitable grooves machined in the necks of the anchor screws 119; their other ends being hooked in grooves machined near the tops of the pins 122 riveted to the preliminary folder plate 117. Also riveted to the preliminary folder plate 117 at its center line and located near its rear edge is the pin 128, which is in line with the head of the stop screw 129 secured in the boss 22a integral with the under side of the bearing 22; said stop screw being held in its adjusted position by the check-nut 130. The purpose of the coil springs 121, the pin 128 and the stop screw 129 will be more fully described hereinafter.

55 Located opposite the seam folder plate 87 is the seam folder plate 96, which is slidably mounted in a suitable guide to allow it to be freely moved forward and backward by a rack and gear sector (not shown) but which is similar to that described in connection with seam folder plate 87, but in this instance the rack and gear sector is located underneath the folder plate to allow the completely wrapped and banded cigars to be ejected along its top surface as illustrated in Fig. 1. The top sur-

face is slightly below the bottom surface of the preliminary folder plate 117 for purposes more fully described hereinafter. The front of said seam folder plate 96 is slotted as at 97, (see Figs. 5 2 and 3) and this slot is located directly opposite the openings 88 and 88a in the seam folder plate 87 and the preliminary folder plate 117. The width of the front of said openings 88 and 88a, and the width of slot 97 is such, to allow the ends 10 of the greatest width of bands to be used to pass through. The rear of said slot 97 is beveled downward toward the back of the plate and its edge rounded off as at 116. This edge folds the gummed end of the band 9 under the cigar which 15 is most clearly illustrated in Figs. 16 and 17. The front or leading edge of the plate 96 is beveled in the opposite direction to that of the edge 116, and on both sides of the slot 97. Secured to the bottom of the plate 96 at its leading edge and on 20 both sides of the slot 97 are the hinged interlocking folders 123 and 123a. (Figs. 3, 4, and 14.) These hinged interlocking folders are held in position by the screws 124. The free or folding blades of the hinged folders are pressed downward 25 against the stops 125 (Figs. 2, 4, 7 and 14) which hold them in their normal positions by means of the small coil springs 126 and 126a; said springs being located between the hinge knuckles and retained in position by the pintle pins 127 and 127a which pass through the center 30 of their coils which is most clearly illustrated in Fig. 14. It will also be seen in this figure that the power of the coil springs is applied to the hinged folding blades by means of one end of said 35 springs being anchored under that portion of said hinged blades which are secured to the plate 96 and their other ends being brought to bear upon the top of the folder blades which is common practice. The operation and purpose of these 40 hinged interlocking folders will be more fully described hereinafter in the description of the operation of my machine.

Referring to Figs. 1, 2, and 3 and more in particular to the latter two, it will be seen that there 45 are two pairs of wrapper end folders. The top folders are designated by the numerals 98 and 98a, and the lower folders by the numerals 99 and 99a. The top folders 98 and 98a are supported on the rods 100, and the folders 99 and 99a are 50 supported on the rods 101; all of said rods pass downward through the table 1, below which, each pair is actuated by its independent cam not shown in the drawings, but which will actuate them in a synchronous manner with the rest of 55 the mechanism as said cams are a part of the main drive mechanism. The end folders are free to move up and down in slots 102 cut in the plate 48 and the slots 103 cut in the plate 20 (see Figs. 2 and 3). The lower edges of the top folders are beveled and grooved to correspond to a bevel and bead on the top edges of the lower folders (see Fig. 15) the purpose of which will be 60 more fully described hereinafter.

When the cigars are completely wrapped and 65 banded, they are ejected from the wrapping and banding position by the ejector finger 104 and the rearward movement of the seam folder plate 96. The ejector finger receives its movement by a means of a combination of levers which are actuated by a cam forming part of the main drive which is not shown in their drawings. As the wrapped and banded cigars are ejected they are brought into position between the guides 105 which are secured to the channels 106 (see Figs. 75 1 and 2). At the termination of the ejecting

movement of the finger 104 and the folder plate 96, the cigars are intermittently moved away from the wrapping and banding mechanism by the reciprocating members 108 (Figs. 1 and 3) which have integral with them the downwardly 5 extending prongs 109. These reciprocating members are connected to the links 110 by pivot screws 111, and said links are connected to the carrying member 112, which is slidably mounted on the shaft 13, by the pivot screws 113. The reciprocating members 108 also receive their motion from the main drive mechanism, and their operation will be more fully described herein. 10

Having thus described my invention in detail, I will now describe its operation. 15

Referring to Fig. 1 it will be seen that the first cigar has been moved up into contact with the centering plate 3, and upon the plunger 5 by a cooperating feed mechanism and the wrapper and band have been fed into position by cooperating 20 wrapper and band feed mechanisms which are not shown. As the cycle of operation starts, the plunger 5 moves the cigar upward, and as the upper left hand edge of it touches the rounded corner formed by the centering plate 4 and its 25 flange 7, this centering plate 4 is pushed toward the left. This movement causes the centering plate 3 to move toward the right an equal distance due to their being connected with a parallel movement mechanism. As the plate 3 moves away, the 30 cigar slides toward it due to the pressure exerted against the plate 4, and this action continues until the distance between the two plates is equal to the width of the cigar. This action absolutely centers the cigars and automatically takes care of any 35 variation. As the plunger 5 continues to move upward it pushes the top surface of the cigar into contact with the wrapper 8, the band 9 and the presser plunger feet 12a and 12b as illustrated in Fig. 1. The continued movement of the plunger 5 causes the cigar to force the presser plunger 12 upward against the tension of the coil springs 18 as illustrated in Fig. 5. This action causes the wrapper to be firmly gripped between the presser plunger feet and the top of the cigar, and the 40 band to be firmly gripped by the rough surface of the fabric tapes 74 and 74a secured in the bottom of presser plunger foot 12a, to prevent its slipping on the smooth surface of the wrapper. Thus the wrapper and band will be held in perfect 45 alignment on the cigar as the continued upward movement of the plunger 5 pushes them into the wrapping and banding position illustrated in Fig. 6. During this movement the wrapper and band have been wrapped around three surfaces of the 50 cigar as shown, the side plates 20 and 48 having forced them downward tightly against the sides of the cigar, with the edges of the wrapper and the ends of the band resting against the beveled tops of the centering plates 3 and 4, as illustrated 55 in Figs. 6 and 7. It will also be noted that the fabric tapes 74 and 74a have also been forced upward with the cigar, wrapper and band, thus insuring against any possibility of the band slipping, and the extra amount of each tape required 60 for this part of the operation was drawn around the rollers 70, 71, and 76, against the tension of their coil springs 73 and 73a which are provided partly for this purpose and to keep the tapes taut during all stages of the operation. Referring 65 again to Fig. 6 it will be seen that the band folding finger, shown in dot and dash lines, has been moved slightly toward the left and this means that the rocker arm 56 has been swung slightly in a clockwise direction and due to this movement, the 70 75

spring 62 secured to its upper end 64, has pressed against the plunger retaining pin 63 (Fig. 1) which in turn is forced against the plate of the plunger 12 to hold the plunger in position against the pull of its coil springs 18 when the plunger 5 starts to move downward prior to the action of the seam interlocking folder plates 87 and 96 as illustrated in Fig. 8.

This holding of the presser plunger in position 10 does not entirely prevent the cigar with its wrapper and band from being dislodged, but merely helps by eliminating the pull of the springs 18; the actual gripping of the cigar, wrapper and its band being performed by the side plates 20 and 48. 15 They are moved toward one another, thereby creating a slight squeezing action against the sides of the cigar to overcome the pull of the coil springs 18 and 73a on the tapes 74 and 74a respectively. This squeezing action is applied by a 20 slight counterclockwise turning of their toggle levers 28. It might be well to mention at this time that the space between the side plates 20 and 48 in their squeezing position is automatically adjusted to take care of various widths of cigars; 25 and this adjustment is made by a cooperating band feed mechanism, which is not shown, when it is adjusted to accommodate the length of band to be used. This adjustment is transferred to the toggle levers 28 by a mechanical connection 30 from the band feed to the toggle push rods 33, see Fig. 3. If a long band is to be used, the push rods 33 will be pulled downward which will spread the plates 20 and 48 farther apart, and if a short band is to be used, the push rods will be moved 35 upward, which would bring the plates closer together. In addition to this adjustment at the band feed, there is also a cam action which will always force the push rods upward to create the squeeze action between the plates at the proper time during the cycle of operation.

40 Referring now to Fig. 8 it will be seen that the interlocking seam folding plates 87 and 117, and 45 96 have moved toward one another. These plates move toward one another at the same time as the plunger 5 moves downward. The forward movement of the folding plate 117 folds its side of the wrapper up close to the bottom of the cigar while the folding plate 96 allows its side of the wrapper to extend downward at an angle 50 due to its beveled leading edge and the clearance between its top surface and the bottom of the cigar. While the folding plates are moving toward one another both sides of the wrapper extend downward at an angle, the side being pushed forward by the plate 96 laying over the edges of 55 the hinged interlocking blades 123 and 123a and the side of the wrapper being pushed forward by the plate 117 extending downward over the edge of the plate and against the incoming edge of the hinged blades. As the two folding members 60 continue to move toward each other, the side of the wrapper overhanging the end of the plate 117 shortens more quickly than the side overhanging the hinged blades due to its being pushed flush against the bottom of the cigar, and as 65 the folder plate 117 reaches the position illustrated, its short overhanging edge passes over the edge of the hinged blades 123 and 123a and forces the side of the wrapper carried forward by the plate 96, downward into the trough formed by the 70 beveled edge and the hinged blades by means of its natural springiness; the sides of the wrapper taking the positions illustrated in the figure referred to, and which is more clearly illustrated in Fig. 11, and the ends of the band taking their

position in the slots 87 and 114 which are provided for this purpose, the slot 114 being provided mostly for the purpose of preventing the gummed end of the band being dragged over the top of the centering plate 3. At the completion 5 of this part of the forward movement of the two folder plates, they both remain idle. The plate 96 being held in this position by its operating mechanism which is not shown in the drawings but which has already been briefly described herein, and the plate 117 is held in its position by means of the pin 128, which is riveted to it, having come into contact with the head of the stop screw 129 which is provided for that purpose. The folder plate 87 continues to move 10 forward and as it does, its beveled leading edge 87a contacts with the underside of the hinged folding blades 123 and 123a, turning them in a clockwise direction against the action of their coil spring 126 and 126a toward the beveled edge of 15 the folder plate 96 as illustrated in Fig. 9. This turning action of the hinged blades folds the edge of the wrapper laying upon them upward and tightly against the edge extending downward over the end of the folder plate 117; which 20 is more clearly illustrated in Fig. 12. This action completes the second step of the forming of the interlocked seam. When the folder plate 87 reaches the position illustrated in Fig. 9, it immediately starts to go backward and the folder 25 plate 96 moves forward at the same rate of speed until they reach the position illustrated in Fig. 10. This forward movement of the plate 96 forces the folded edges of the wrapper upward over the top of its beveled edge and against 30 the underside of the plate 117, which presses down and creases the folded edges. Due to the triple thickness of the wrapper being forced between the two plates, the plate 117 which is made from very thin spring steel is forced to bend 35 40 slightly upward which is illustrated most clearly in Fig. 13, and it is this action that creases down the fold. The plate 117 is held in the position illustrated in Figs. 10 and 13 by the action of its coil springs 121 which are provided for this 45 purpose. This action completes the third step of the forming of the interlocked seam and during the operation illustrated in Figs. 9 and 10, the bottom end folders 99 and 99a have moved up to the position illustrated in Fig. 15 in preparation 50 to fold and crease the ends of the wrapper which extend beyond the ends of the cigar. This view also clearly illustrates the position of the gummed end of the band in the slot 114.

At this point in the cycle of operation, with the 55 seam folders in the position as shown in Fig. 10, the rocker arm 56 is moved in a counter-clockwise direction until it has reached the position illustrated in Fig. 16. This movement of the rocker arm releases the pressed plunger, but the 60 downward pull of its springs 18 cannot dislodge the partly wrapped and banded cigar because the side plates 20 and 48 are still squeezing against it, and they in turn are aided in retaining the cigar in position by the seam folder 96 which 65 still remains partly underneath it. The movement of the rocker arm has moved the band folder finger 67 forward. This movement causes the roller 10 to press the fabric tape 74 against the end of the band, forcing it upward tightly against 70 the already folded wrapper, said upward pressure of the roller being obtained from the spring 68 which presses against the tongue 69. During this forward movement of the band folder finger the seam folder plate 117 has been moved back- 75

ward and drawn from between the folded seam by means of the stop screws 118 hitting the back of the slots 120 in said plate 117. When the finger has reached the limit of its movement as illustrated in Fig. 11, it immediately starts to recede with the seam folder plate 96 following it until the parts take the position shown in Fig. 17, the folder plates 87 and 117 having moved backward beyond their normal positions to accommodate the folder 96. During the forward movement of the seam folded plate 96, the beveled edge 116 which forms the rear of the slot 97, came into contact with the band and forced it tightly upward against its other end which was placed in position by the finger 67. This last folded end of the band is the gummed end which was moistened before the band was fed into position and the pressure of the seam folder plate 96 securely seals the two ends of the band together. While this banding operation was taking place, the plunger 5 moved down to its normal position (Fig. 17) and the ejector finger 104 has been moved forward and down upon the top of the wrapped and banded cigar. During this operation, the end folders 98, 98a, and 99 and 99a have been brought together as illustrated in Fig. 18. These folders press simultaneously against the top and bottom surfaces of the ends of the folded and interlocked wrapper, and as they continue to move toward one another, bringing these surfaces with them, the side surfaces collapse inwardly because the side plates 20 and 48 prevent them from going outward. This makes what is known as a bellows fold which is tightly squeezed together by the beveled edges of these end folders, the beads and grooves of which pinch and score the wrapper. This pinching and scoring causes the folded ends to spring inward toward the cigar as illustrated in Fig. 20, when the folders release them.

Referring to Fig. 19 it will be seen that the presser plunger 12 and the side plate 48 have been raised, a new wrapper and band have been brought into position, and another cigar has been moved into position over the plunger 5. The presser plunger and side plate have been raised to allow the ejector finger 103 and the seam folder plate 96 to remove the wrapped and banded cigar when they return to their normal positions illustrated in Fig. 1, carrying the cigar with them. The presser plunger is raised by the slotted link 31 engaging the pin 79 of the bracket 78, said link being actuated by the lever 82 and the push rod 33. The side plate 48 has been raised by the movement of the lever 46.

When the completely wrapped and banded cigars move into the ejector position illustrated in Fig. 1, the reciprocating members are in a raised position. They are then lowered and pulled toward the right, the prongs 109 gripping behind the cigars move them along until the last ejected cigar reaches the position of the previously ejected cigar.

In accordance with the provisions of the patent statutes, I have described my invention, but I desire it understood that it is not confined to the particular form shown and described, the same being merely illustrative, and that the invention can be carried out in other ways without departing from the spirit of my invention, and therefore, I claim broadly the right to employ all equivalent instrumentalities coming within the scope of the appended claims, and by means of which, objects of my invention are attained and

new results accomplished; as it is obvious that the particular embodiments herein shown and described are only some of many that can be employed to attain these objects and accomplish these results.

Having now described my invention, what I claim and desire to secure by Letters Patent, is:

1. In a cigar wrapping machine, means to apply a wrapper to the upper side of a cigar, means to elevate said cigar with the wrapper into a stationary wrapping position, clamping means to hold the cigar with the longitudinal edges of the wrapper depending from the sides of the cigar, in this position, means to complete the wrapping by folding a wrapper overlappingly around the underside of said cigar, means to interlock the overlap of the wrapper, means to fold and means to crease the free ends of said wrapper, while the cigar is continuously held stationary during these various operations.

2. In a cigar wrapping machine, means to carry a cigar simultaneously with an adjacent wrapper into a wrapping position, said wrapper having a greater width than the circumference of the cigar, means to hold said cigar stationary in this position, means cooperating with said holding means to automatically fold the wrapper around the underside of the cigar and means to interlockingly fold the surplus width of said wrapper over the cigar in a longitudinal direction while the cigar does not change its position throughout these consecutive folding operations.

3. In a wrapping machine, means to superimpose a wrapper of greater width and length than the circumference and the length of the object to be wrapped over said object, means to carry said object with the superimposed and laterally depending wrapper into a stationary wrapping position, clamping means to hold it in said position, automatic means to fold the wrapper around the underside of the object and automatic means to seal the surplus area of the wrapper over the surface of the object by interlocking folds, all of said means adapted to act cooperatively on said wrapper on the object while the latter remains continuously in the same position throughout these folding operations.

4. In a cigar wrapping and banding machine, means for elevating a cigar and simultaneously therewith folding a wrapper and a band against its sides and auxiliary means, mechanically and operably combined to interlock the seam edges of the wrapper and seal the band across the edges while the cigar is in raised position and held stationary during the operations of said auxiliary means.

5. In a machine for wrapping an object while the same is held stationary in one place while the wrapping operations are completed, means to convey the object together with the adjacent wrapper into said place, means comprising a pliable spring-actuated band, forming a permanent portion of the operating mechanism, fixedly held at a point, directly adjacent to the object, and adapted to be folded around the wrapper as a guiding girdle, to fold a wrapper around said object and means to seal the overlapping edges of the wrapper.

6. In a cigar wrapping and banding machine, adapted to apply a wrapper of regenerated cellulose and a superimposed band to a cigar, while the latter is held stationary, substantially during the entire wrapping and banding operation, means, comprising a pliable ribbon, resiliently

fastened at the ends, but fixedly in the middle where it adjoins the side of the article, and adapted to be folded around the wrapper and band as a guiding girdle, to fold said wrapper and band around the cigar, and means to close said wrapper and superimposed band.

5 7. In a cigar wrapping machine, automatic means to convey a rectangular wrapper to a cigar and deposit it on its upper side, means to ele-

10 vate said cigar with the longitudinal wrapper edges depending from the sides of the cigar into a stationary wrapping position, self-centering means, cooperating with the elevating means, to sideshift the cigar with the wrapper during the

15 15 rise into a central wrapping position, self-adjusting clamping means to hold the partly wrapped cigar in a stationary position, means to fold the wrapper across the underside of the cigar in this position and means to interlocking-
20 ly fold the free edges of the wrapper together while the cigar is held continuously in the same position throughout these different folding operations.

25 8. In a cigar machine of the character described means to elevate a cigar with a superimposed wrapper into a stationary position while simultaneously folding the longitudinal wrapper

edges downwardly over the sides of the cigar, clamping means to hold the cigar stationarily during the following operations, and cooperative folding mechanisms for completing the wrapping of the cigar, with auxiliary cooperative means for 5 interlocking the seam edges of the wrapper, said operations being performed at the same place by the same combined mechanisms in various successive motions.

9. In a cigar machine of the character de- 10 scribed means to elevate a cigar with a superim-
posed wrapper and a band into a stationary po-
sition while simultaneously folding the longi-
tudinal wrapper edges and band ends down-
wardly over the sides of the cigar, clamping 15 means to hold the cigar stationarily during the
following operations and cooperative folding
mechanisms for completing the wrapping and
banding of the cigar, with auxiliary cooperative
means for interlocking the seam edges of the 20
wrapper, coordinated and mechanically com-
bined means for overlapping the band ends across
the wrapper seam, said wrapping and banding
operations being performed at the same place 25
by the same combined mechanisms in various
successive motions.

FRANCIS X. MALOCSSAY.
